UNITED STATES PATENT OFFICE.

JOHN M. ROSS AND JOHN S. RIDDELL, OF FROBISHER, SASKATCHEWAN, CANADA.

DISK-GRINDER.

No. 872,372.

Specification of Letters Patent.

Patented Dec. 3, 1907.

Application filed May 23, 1906. Serial No. 318,415.

To all whom it may concern:

Be it known that we, JOHN M. ROSS, blacksmith, and JOHN S. RIDDELL, merchant, both of Frobisher, in the Province of Saskatchewan, Canada, have invented certain new and useful Improvements in Disk-Grinders, of which the following is a specification.

Our invention relates to improvements in disk grinders and the objects of our invention are to provide an exceedingly cheap, simple and easily adjustable grinder for the purpose of grinding and sharpening the disks usually employed in connection with the various forms of disk plows, disk harrows, disk drills as well as plow colters and by means of which when the disk has once been placed in position in the machine it will not be necessary to move it therefrom until the whole of the disk has been ground; and it consists essentially of a suitable base, a grinding wheel mounted thereon, a disk supporting shaft, a tiltably supported frame supporting the shaft, means for holding the same in any adjusted position, means for moving the frame to and from the grinding wheel and means for adjusting the position of the shaft relative to the frame, the various parts of the device being constructed and arranged in detail as hereinafter more particularly described.

Figure 1 is a perspective view of our disk grinder. Fig. 2 is a sectional view through the top of the disk. Fig. 3 is a sectional detail showing the corrugated plate to which the shaft supporting frame is adjustably secured. Fig. 4 is a sectional view on the line 2—2 Fig. 3.

In the drawings like letters of reference indicate corresponding parts in each figure.

A is the base of our machine which may be of any desirable construction preferably having the grinding wheel B of emery or the like mounted on a horizontal shaft a supported in bearings b from the top of the base. The grinding wheel is preferably rotated by means of a belt C which connects a pulley c on the shaft a to a large driving wheel d which is supported on the base and has thereon a hand operating lever e. If desired however, the driving wheel d might be connected to a suitable source of mechanical power.

D is a disk supporting shaft on the upper end of which the disk E being ground is mounted, the circumference of the disk being in a plane substantially normal to the shaft.

Preferably the disk is attached to the shaft by means of a fixed collar f abutting the side of the disk to be ground and a plate g abutting the side of the disk which is not to be ground and being held in contact therewith by means of a nut i screwed on the end of the shaft D. To deaden the sound produced by the disk while being ground we insert an annular ring j of leather, rubber or like material between the disk E and the plate g.

The shaft D is slidably held in the two outwardly extending arms k and l of a frame F which is pivoted by means of a bolt m to a plate G. To hold the frame in any position to which it may be tilted we provide integral therewith a projecting tenon n which is adapted to engage one of a plurality of radial slots o provided in the surface of the plate G. The plate G is itself slidably held in position on a fixed bar H supported from the frame by means of a bracket p, preferably by providing a slot q in the side of the plate into which fits the bar H. The plate is held in any position to which it has been adjusted by means of the bolt m which extends through a slot r in the bar H.

I is a lever pivoted at s to the frame and provided intermediate of its length with a slot t through which extends the shaft D.

On the shaft above the slot t a collar J is adjustably secured by means of a small set-screw the bottom of the collar which will normally rest on the top of the lever being formed of a suitable bearing material. The lever is held in position by means of a dog K held in position by means of a spring u and the end v of which engages the lower arm k of the frame. An operating handle w is pivoted near the end of the lever I and connected by means of a bar or wire x to the dog K whereby the same may be withdrawn from contact with the arm k when it is desired to adjust the machine. To limit the upward movement of the shaft the collar y is adjustably secured thereon.

In the operation of our device the disk to be ground is secured on the end of the shaft D as hereinbefore described. The angular position of the shaft is adjusted by tilting the frame F and the distance of the disk from the emery wheel is adjusted by means of the plate G sliding on the bar H. The vertical position of the disk is adjusted by means of the collar J on the shaft. By means of these three adjustments the exact part of the disks

desired to be ground can be brought bearing against the emery wheel which when rotating will sharpen it as desired.

The position of the shaft D is slightly in front of the surface of the emery wheel B whereby when the emery wheel is rotating it will grind the disk and will gradually turn it with the shaft D. Thus an annular portion of the disk will be ground evenly all around and when it is desired to grind another portion of it the inclination of the disk to the emery wheel is adjusted by means of the tilting of the frame F. The height of the collar J on the shaft D should be just sufficient to allow the disk E to bear slightly on the emery wheel.

It will be observed that after once putting the disk on the shaft it is not necessary to again handle it except to remove it when completely sharpened, as by the adjustment of the various parts as hereinbefore described the edge of the disk may be completely ground. It is evident that the sharpening device may be applied to other forms of disks and if desired the whole surface of the disk could be ground or polished.

While we have described with great particularity of detail one specific embodiment of our invention yet it is not to be understood therefrom that the construction is limited thereto as certain changes might be made in the details thereof within the scope of the appended claims without departing from the spirit of our invention.

35 What we claim as our invention is:

1. An improved disk grinder comprising a grinding wheel, means for rotating the same, a disk supporting shaft, vertically movable and gravity held in its lowest position, a frame supporting the same, a tenon on the frame, a plate, a plurality of radial grooves therein, adapted to be engaged by said tenon and means for supporting the plate, as and for the purpose specified.

40 2. An improved disk grinder comprising a grinding wheel, means for rotating the same, a frame a shaft slidably supported therein, means for pivotally supporting the frame,

means for holding the frame in any position to which it has been adjusted, a lever pivoted to the frame having a slot therein through which the shaft extends, a collar adjustably secured on the shaft, a spring-held dog pivoted to the lever normally engaging the frame, and means operably from the end of the lever for removing the dog from engagement with the frame as and for the purpose specified.

3. An improved disk grinder comprising a suitable base, a shaft horizontally supported on the top thereof, a grinding wheel on the same, means for rotating the shaft, a bar laterally extending from one side of the base, a plate slidably secured thereon, means for holding the plate in any adjusted position, a plurality of radial grooves in said plate, a frame, a tenon thereon engaging the grooves in the plate, a shaft slidably supported in the frame and means for holding the shaft in any position relative to the frame as and for the purpose specified.

4. An improved disk grinder comprising a suitable base, a shaft horizontally supported on top thereof, a grinding wheel on said shaft, means for rotating the shaft, a bar laterally extending from one side of the base and having a longitudinal groove therein, a plate having a plurality of radial grooves therein, a U-shaped frame, a tenon thereon adapted to engage the grooves in the plate, a bolt extending through said frame, plate and slot in the bar, a disk supporting shaft extending through the arms of the frame, an adjustable collar thereon, a lever pivoted to the shaft having a slot therein through which the shaft extends and a spring-held dog on said lever engaging the lower arm of the frame as and for the purpose specified.

Signed at Saskatchewan, this eighth day of May, 1906.

JOHN M. ROSS.
JOHN S. RIDDELL.
